CLAIM

The ornamental design for a ladder rack assembly for a cooking cavity, as shown and described.

DESCRIPTION

FIG. 1 is a top perspective view of a ladder rack assembly for a cooking cavity, according to the first embodiment of the claimed design;

FIG. 2 is a bottom perspective view thereof;

FIG. 3 is a front perspective view thereof;

FIG. 4 is a front elevation view thereof;

FIG. 5 is a side elevation view taken along line V-V indicated in FIG. 4;

FIG. 6 is a front elevation cross-sectional view taken along line VI-VI indicated in FIG. 5;

FIG. 7 is a top perspective view of a ladder rack assembly for a cooking cavity, according to the second embodiment of the claimed design;

FIG. 8 is a bottom perspective view thereof;

FIG. 9 is a front perspective view thereof;

FIG. 10 is a front elevation view thereof;

FIG. 11 is a side elevation view taken along line XI-XI indicated in FIG. 10;

FIG. 12 is a front elevation cross-sectional view taken along line XII-XII indicated in FIG. 11;

FIG. 13 is a top perspective view of a ladder rack assembly for a cooking cavity, according to the third embodiment of the claimed design;

FIG. 14 is a bottom perspective view thereof;

FIG. 15 is a front perspective view thereof;

FIG. 16 is a front elevation view thereof;

FIG. 17 is a side elevation view taken along line XVII-XVII indicated in FIG. 16;

FIG. 18 is a front elevation cross-sectional view taken along line XVIII-XVIII indicated in FIG. 17;

(Continued)

FIG. 19 is a top perspective view of a ladder rack assembly for a cooking cavity, according to the fourth embodiment of the claimed design;
 FIG. 20 is a bottom perspective view thereof;
 FIG. 21 is a front perspective view thereof;
 FIG. 22 is a front elevation view thereof;
 FIG. 23 is a side elevation view taken along line XXIII-XXIII indicated in FIG. 22; and,
 FIG. 24 is a front elevation cross-sectional view taken along line XXIV-XXIV indicated in FIG. 23.

In the claimed drawings: The portions of the article shown in broken line form no part of the claimed design. The broken break lines in FIGS. 6, 12, 18, and 24 form no part of the claimed design. The broken cross-section lines in FIGS. 4, 5, 10, 11, 16, 17, 22, and 23 form no part of the claimed design.
